Primary Examiner — Cynthia R Underwood*(74) Attorney, Agent, or Firm* — Maier & Maier, PLLC(57) **CLAIM**

The ornamental design for a meal box, as shown and described.

DESCRIPTION

FIG. 1 is a perspective view of a meal box showing our new design;

FIG. 2 is a front view thereof, for which the rear view, the left side view and the right side view are the same;

FIG. 3 is a top view thereof; and,

FIG. 4 is a bottom view thereof.

The broken lines showing portions of the meal box form no part of the claimed design.

1 Claim, 4 Drawing Sheets
